D11-1614

OR D2,352

EX

No 2,352

PATENTED

JUL 3 1866

J. H. Ward
a. Leibig

John Rogers.

Des. 2352

Design of New York N.Y.

Patent No. 2,391,852 Dated July 10, 1940

Design of Figure

Shirtwaist dress with a belt, printed in various colors.

Shoulder straps.

First known that is with a basement body and breast pocket. It has a belt, a belt buckle, and is produced in various original designs for men and women and it is hereby declared that the aforesaid is a new and useful design.

081 2352

descriptions of the characters

The geographical name of this figure is not indicated. He is seated on a large black stool which is mostly seated on top of a high board. A small tiger is seated on his right, and a small tiger is seated on his left, which he is holding. He is wearing a tiger's tail, little tiger seated on the ground, is holding a tiger's tail. He is holding a tiger's tail. He is holding a tiger's tail. He is holding a tiger's tail. He is holding a tiger's tail.

Colinus virginianus